UNITED STATES PATENT OFFICE.

FRANK E. MILLER, OF NEW YORK, N. Y.

BONE RESECTOR.

1,423,866.

Specification of Letters Patent. Patented July 25, 1922.

Application filed April 24, 1918, Serial No. 230,421.

Renewed December 22, 1921. Serial No. 524,295.

To all whom it may concern:

Be it known that I, FRANK E. MILLER, a citizen of the United States, and a resident of New York city, county and State 5 of New York, have invented a certain new and useful Bone Resector, set forth in the following specification.

This invention relates to surgical instruments. The object of the invention is to 10 produce a resector suitable for the correction of septal deviation without resort to any cutting and removal either of the bony structure or of the mucous covering.

I have found from my experience and ob- 15 servation that, in a large measure, the many operations on the septum that are being practiced, deform the nose and destroy acoustical balance and many times create a dry, catarrhal condition besides from mal- 20 position forming adhesions.

The instrument which I have produced is serviceable in severing a warped or mal-formed septum, so far as its bony structure is concerned, but without injuring the mu- 25 cous covering.

In carrying out my desired construction I propose to provide a pair of blunt-edged operating wedge-shaped members constrained to move in slightly separated 30 parallel planes and combined with means whereby a powerful shearing action may be imparted to the said members.

The above will better be understood by reference to the following specification, 35 which describes an illustrative embodiment shown merely for purposes of illustration in the accompanying drawings, which form a part hereof, in which like characters designate corresponding parts in the several 40 figures, and in which

Figure 1 is a perspective view of my complete resector;

Figure 2 is a front elevation of the same;

Figure 3 is a side view taken along the 45 line III—III of Figure 2;

Figure 4 is a horizontal section through line IV—IV of Figure 2; and

Figure 5 is a horizontal section drawn to double size along line V—V of Figure 3.

50 A pair of symmetrical operating mem- bers 1 and 2 are formed preferably wedge-shaped and of substantially triangular cross section, as shown best in Figure 5. Geometri- cally, they may be described as triangular 55 prisms. The blunt operating edges are in-

dicated by *a* and it should be noted that the contiguous faces *b* are parallel and should be laterally separated preferably approximately $\frac{1}{16}$ of an inch.

The members 1 and 2 are operated by a 60 pair of necks 3 and 4, respectively mechani- cally connected to the members 1 and 2 and preferably forming integral outer extensions thereof. The necks 3 and 4 should be bowed, as indicated best in Figure 1, to escape and 65 clear the parts of the nasal structure which do not require operation.

The necks 3 and 4 continue respectively into manually operable handles 5 and 6 of the forceps type. Between the neck 3 proper 70 and the handle 5 proper substantially one-half of the metal is cut away to form the pivoting ledge *c*, the plane of which is parallel to and intermediate the faces *b* of the operating members 1 and 2. Likewise the 75 metal of the neck and arm structure 4 is cut away to form the pivoting ledge *d*. The shank *e* is provided with a keyhole slot *f* to take the locking pivoting pin *g*, mounted to upstand from the ledge *c* of shank *h*. 80 It is obvious that the two parts of the resector may be disconnected by bringing the two parts substantially at right angles to one another so that the head of the pin *g* 85 can pass through the slot *f*.

In as much as it is highly essential in this instrument that a true parallel movement between the operating members 1 and 2 be effected without any variation, even when considerable force is being exerted 90 in the lateral separation between the faces *b*, it is preferred to provide guiding means in addition to the ledges *c* and *d* and the slot and pin *f* and *g*. It is also an objective to accomplish this supplemental guiding 95 without weakening the structure. To this end I cut a slot *i* in the shank end of the handle 6, preferably so that one wall *j* of this slot is in the same plane as the ledge *d*.

The other wall *k* of this slot is parallel to the wall *j* and separated therefrom an amount sufficient to snugly engage the parallel side walls of the tongue *l* projecting out from the shank end of the handle 5. The outer edge *7* of this tongue should be cut 100 arcuate about the axis of the pin *g* as its axis. The corresponding face of the slot *i* may have similar arcuate contour.

It should be noted that the entire structure of my resector, so far as its pivoting is 110

concerned, is of the scissors genus,—that is, the operating blades are respectively on the same side of the median plane as are the sliding pivoting ledges.

5. What I claim and what I desire to secure by United States Letters Patent is:—

1. A bone resector comprising, a pair of dull operating blades; a pair of relatively pivotable necks respectively mounting said blades so that said blades are guided into and out of approximate juxtaposition with constant lateral separation; and a pair of manually operable handles respectively connected with said necks for effecting the operating movement of said blades.

2. In a resector, a pair of shearing crushers adapted to move in separated parallel planes; means comprising a pair of handles for operating said crushers; and guiding means for said crushers comprising a tongue and slot formed respectively on said handles.

3. A resector comprising, a pair of blunt edged operating members; relatively pivotable necks for constraining said members to move in separated parallel planes; and a pair of manually operable handles for effect-

ing the operative movement of said members.

4. A resector comprising a pair of relatively cooperating shearing crushers having longitudinal blunt operating edges; and means for effecting a relative operating movement of said crushers in separated parallel planes from open position, in which the part to be crushed may be engaged by a longitudinal or endwise engaging movement of the resector to closed position, in which said crushers are approximately juxtaposed.

5. A surgical instrument comprising a pair of handles and operating members arranged like a pair of scissors with the operating parts on opposite sides of the swiveling plane, said operating parts comprising longitudinal blunt edged shearing members permanently laterally spaced; and guiding means comprising a tongue formed on one handle and a mating slot on the other handle.

In testimony whereof I have signed my name to this specification, this 25th day of March, 1918.

FRANK E. MILLER.
